UNITED STATES PATENT OFFICE

OEL E. WARDNER, OF NEW BRITAIN, CONNECTICUT, ASSIGNOR TO NORTH & JUDD MANUFACTURING COMPANY, OF NEW BRITAIN, CONNECTICUT, A CORPORATION OF CONNECTICUT

DESIGN FOR A BELT BUCKLE

Application filed May 10, 1929. Serial No. 31,169. Term of patent 3½ years.

To all whom it may concern:

Be it known that I, OEL E. WARDNER, a citizen of the United States, and a resident of New Britain, in the county of Hartford, State of Connecticut, have invented a new, original, and ornamental Design for a Belt Buckle, of which the following is a specification, reference being had to the accompanying drawing, forming part hereof.

In the accompanying drawing, Figure 1 is a front perspective view of a belt buckle showing my new design, and

Fig. 2 is a cross-sectional view on line 2—2 of Fig. 1.

I claim:

The ornamental design for a belt buckle, as shown.

OEL E. WARDNER.
